(57) **CLAIM**

The ornamental design for an offset pivot hinge, as shown and described.

DESCRIPTION

FIG. 1 is a front top perspective view of an offset pivot hinge showing my new design in a first position;

FIG. 2 is a rear top perspective view of the offset pivot hinge of FIG. 1 in a second position;

FIG. 3 is a front bottom perspective view of the offset pivot hinge of FIG. 1 in the first position;

FIG. 4 is a rear bottom perspective view of the offset pivot hinge of FIG. 1 in the second position;

FIG. 5 is a right side view of the offset pivot hinge of FIG. 1 in the first position;

FIG. 6 is a left side view of the offset pivot hinge of FIG. 1 in the first position;

FIG. 7 is a front elevational view of the offset pivot hinge of FIG. 1 in the first position;

FIG. 8 is a rear elevational view of the offset pivot hinge of FIG. 1 in the first position;

FIG. 9 is a top view of the offset pivot hinge of FIG. 1 in the first position;

FIG. 10 is a bottom view of the offset pivot hinge of FIG. 1 in the first position;

FIG. 11 is a front top perspective view of a second embodiment of an offset pivot hinge showing my new design in a first position;

FIG. 12 is a rear top perspective view of the offset pivot hinge of FIG. 11 in a second position;

FIG. 13 is a front bottom perspective view of the offset pivot hinge of FIG. 11 in the first position;

FIG. 14 is a rear bottom perspective view of the offset pivot hinge of FIG. 11 in the second position;

FIG. 15 is a left side view of the offset pivot hinge of FIG. 11 in the first position;

FIG. 16 is a right side view of the offset pivot hinge of FIG. 11 in the first position;

FIG. 17 is a rear elevational view of the offset pivot hinge of FIG. 11 in the first position;

FIG. 18 is a front elevational view of the offset pivot hinge of FIG. 11 in the first position;

FIG. 19 is a top view of the offset pivot hinge of FIG. 11 in the first position; and,

FIG. 20 is a bottom view of the offset pivot hinge of FIG. 11 in the first position.

The broken lines illustrate unclaimed features that form no part of the claimed design.
